(57) **CLAIM**

The ornamental design for a remote control holder, as shown and described.

DESCRIPTION

FIG. 1 is a perspective view of a remote control holder; FIG. 2 is a bottom perspective view of the remote control holder of FIG. 1;

FIG. 3 is a top view of the remote control holder of FIG. 1; FIG. 4 is a left-side view of the remote control holder of FIG. 1, the right-side view of the remote control holder being identical the left-side;

FIG. 5 is a bottom view of the remote control holder of FIG. 1; and,

FIG. 6 is a front view of the remote control holder of FIG. 1, the rear view of the remote control holder being identical to the front view.

The broken lines are directed to unclaimed portions and form no part of the claimed design.
